CLAIM

The ornamental design for a fence panel as shown and described.

DESCRIPTION

FIG. 1 is a perspective view of a fence panel;
FIG. 2 is a front view of the fence panel;
FIG. 3 is a left side view of the fence panel;
FIG. 4 is a top view of the fence panel;
FIG. 5 is a rear view of the fence panel;
FIG. 6 is a right side view of the fence panel;
FIG. 7 is a bottom view of the fence panel;
FIG. 8 is an enlarged fragmentary view taken as indicated in FIG. 1;
FIG. 9 is an enlarged fragmentary view taken as indicated in FIG. 1;
FIG. 10 is an enlarged fragmentary view taken as indicated in FIG. 1;
FIG. 11 is a perspective view of a plurality of the fence panels in a stacked arrangement; and,
FIG. 12 is an enlarged fragmentary view taken as indicated in FIG. 11.

The broken line areas in the figure drawings show environmental subject matter that forms no part of the claimed design.

The dash-dash broken line circles depict the limits of the enlarged views and form no part of the claimed design.

1 Claim, 8 Drawing Sheets
